UNITED STATES PATENT OFFICE.

JOHN G. LOBSTEIN, JR., OF CHICAGO, ILLINOIS, ASSIGNOR TO PASSOW & SONS, OF CHICAGO, ILLINOIS, A CORPORATION OF ILLINOIS.

DESIGN FOR A BILLIARD-TABLE.

43,462.

Specification for Design.

Patented Jan. 21, 1913.

Application filed October 26, 1912. Serial No. 728,008. Term of patent 7 years.

To all whom it may concern:

Be it known that I, JOHN G. LOBSTEIN, Jr., a citizen of the United States, residing at Chicago, in the county of Cook and State of Illinois, have invented a new, original, and ornamental Design for a Billiard-Table, of which the following is a specification, reference being had to the accompanying drawing, forming part thereof.

The figure is a perspective view of a billiard table, showing my new design.

I claim:

The ornamental design for a billiard table, as shown.

JOHN G. LOBSTEIN, JR.
